Primary Examiner — Andrew T Nemeth

(57) **CLAIM**

The ornamental design for a dog trainer remote control, as shown and described.

DESCRIPTION

FIG. 1 is a front, right and top perspective view of a dog trainer remote control showing my new design; FIG. 2 is a rear, left and bottom perspective view thereof; FIG. 3 is a front view thereof; FIG. 4 is a rear view thereof; FIG. 5 is a left side view thereof; FIG. 6 is a right side view thereof; FIG. 7 is a top plan view thereof; and, FIG. 8 is a bottom plan view thereof.

The broken lines in the figures illustrate portions of the dog trainer remote control that form no part of the claimed design.
